Des. 237,911
Patented Dec. 2, 1975

237,911

DRY SHAVER OR SIMILAR ARTICLE

Maarten Willem van Lelyveld, Drachten, and Knut Otto Yran, Eindhoven, Netherlands, assignors to U.S. Philips Corporation, New York, N.Y.

Filed Aug. 31, 1973, Ser. No. 393,473

Claims priority, application Switzerland Mar. 1, 1973

Term of patent 14 years

Int. Cl. D28—03

U.S. Cl. D95—3 A

FIG. 1 is a perspective view of a dry shaver or similar article showing our new design;

FIG. 2 is a left side elevational view in a standing position;

FIG. 3 is a right side elevational view thereof;

FIG. 4 is a front elevational view thereof;

FIG. 5 is a rear side elevational view thereof;

FIG. 6 is a top plan view thereof; and

FIG. 7 is a bottom plan view thereof.

We claim:

The ornamental design for a dry shaver or similar article, as shown and described.
